UNITED STATES PATENT OFFICE.

WILLIS H. PRATT, OF HARTFORD, CONNECTICUT, ASSIGNOR TO THE ARROW ELECTRIC COMPANY, OF HARTFORD, CONNECTICUT, A CORPORATION OF CONNECTICUT.

SNAP-SWITCH BASE.

1,135,138.

Specification of Letters Patent. Patented Apr. 13, 1915.

Application filed October 28, 1914. Serial No. 869,031.

To all whom it may concern:

Be it known that I, WILLIS H. PRATT, a citizen of the United States, residing at Hartford, in the county of Hartford and State of Connecticut, have invented a new and useful Improvement in Snap-Switch Bases, of which the following is a specification.

This invention relates to the construction of the bases of rotary snap electric switches and the means for supporting the operating mechanism. The bases of these switches are usually formed of circular blocks of porcelain with recesses in the upper face for receiving the locking, latching and releasing mechanism. In order to have the supporting parts and the locks fit the base so as to properly support the actuating mechanisms it has been considered necessary to make the bases quite accurate and this is somewhat difficult in view of the friability or brittleness of the material and the change it is likely to undergo during the process of manufacture.

The object of this invention is to provide a construction which renders it unnecessary to use extreme caution in manufacture, and which produces bases that are strong and not liable to become damaged or broken in use, and in which the locks and supporting parts may be very easily and securely fastened in such manner that the operating mechanisms will always operate freely and efficiently.

Figure 1 of the accompanying drawings shows a plan of a base of a snap switch provided with a lock plate and spindle support designed according to this invention. Fig. 2 shows a plan of the base without the lock and spindle support. Fig. 3 shows a bottom view of the base. Fig. 4 shows a central section of the base and the lock and spindle support on the plane indicated by the dotted line 4-4 on Fig. 1. Fig. 5 shows a central section of the base only.

The circular base 1 is made in the usual way of porcelain with a recess 2 in the upper surface and an opening 3 of considerable size through the middle. In the bottom 50 of the recess are four depressions 4 arranged approximately tangential with relation to the central opening. In the underside of the base is a recess 5 and in the face of this around the central opening through the base 55 is an annular depression 6.

The lock plate 7 has four outwardly extending arms with up-turned lugs 8 at the extreme ends. This lock plate is set into the recess in the top with its arms lying in the tangential depressions in the bottom of the 60 recess so that the top of the plate is approximately flush with the surface of the recess, the lugs only projecting upward above. An opening is made through the center of the lock plate and around this 65 opening the plate is depressed for receiving the angular head 9 of the spindle supporting hub 10 that extends down through the lock plate. On the underside of the base is a reentrant washer 11, the edge of which 70 lies in the depression 6, while the upwardly extending body portion enters the hole through the block. The supporting hub extends through this washer and on the threaded end of the hub outside of the 75 washer is a nut 12. When this nut is screwed up the lock plate and washer are tightly clamped in place between the head of the hub and the nut.

With this construction the lock plate is 80 securely held in position and it cannot be turned under the blows which it receives from the operating mechanism of the switch when snapped. The securing nut on the end of the hub is located in the reentrant 85 washer, leaving space below for such other parts of the switch as are necessary. The opening through the base with this construction can be made quite large so as to save porcelain and lighten the structure, 90 and this large opening permits of the easy assembling and fastening of the parts. Furthermore, the walls of the opening through the base do not have to be made of exact thickness and in fact they can be quite thick 95 so as to afford ample strength for the strong and secure fastening of the parts.

The invention claimed is:

1. A snap switch base having a recess in its upper face and a central opening, with 100 depressions in the bottom of the recess extending tangentially with relation to the central opening, a lock plate with outwardly extending arms and up-turned lugs located in the recess with the arms lying in the 105 depressions, a washer arranged on the underside of the base, a hub extending through the lock plate and the washer and having an angular head lying in a correspondingly shaped depression in the lock plate, and a 110

nut screwed on the hub against the underside of the washer.

2. A snap switch base having a recess in its upper face and a central opening, with 5 depressions in the bottom of the recess extending outwardly from said opening, a lock plate with outwardly extending arms and up-turned ends in the recess with the arms lying in said depressions, a reëntrant washer 10 on the underside of the base, a hub extending through the lock plate and washer, said hub having an angular head lying in a correspondingly shaped depression in the lock plate, and a nut screwed on the end of the 15 hub and lying within the reëntrant washer.
3. A snap switch base having a recess in its upper face and a central opening with 20 depressions in the bottom of the recess extending outwardly from said opening, said base in its bottom face having a recess with a depression around the central opening, a lock plate having outwardly extending arms with up-turned ends located in the recess in the upper face of the base with the arms 25 occupying the depressions, said lock plate having a central opening and an angular depression around said opening, a reën-

trant washer with its edge occupying the depression in the underside of the base and its body extending into the central opening, 30 a hub extending through the lock plate and the washer and having an angular head occupying the angular depression in the lock plate, and a nut turned on the threaded end of the hub and bearing against the underside of the washer in the reëntrant portion.

4. A snap switch base having a recess in its upper face, a recess in its lower face and a central opening, a lock plate having outwardly extending arms with upturned ends 35 located in the recess in the upper face of the base, said lock plate having a central opening, a reëntrant washer located in the recess in the lower face of the base and having its reëntrant portion extending into the 40 central opening, a hub extending through the lock plate and the washer, and a nut turned on the threaded end of the hub and bearing against the underside of the washer in the reëntrant portion.
